Primary Examiner — Rashida Johnson(74) Attorney, Agent, or Firm — Banner & Witcoff, Ltd(57) CLAIM

The ornamental design for a hooded garment, as shown and described.

DESCRIPTION

FIG. 1 is a perspective view of a hooded garment showing our new design in an in-use configuration;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines immediately adjacent to the shaded area represent unclaimed boundaries of the design. The contrast in shading represents a contrast in appearance only and does not represent any particular color, material, texture or finish. The broken lines showing the remainder of the hooded garment are for environmental purposes only and form no part of the claimed design.
